PORTABLE ELECTRIC DRILL UNIT

Robert O. Ernest, Oak Park, and Earl Daniel Metko,
Chicago, Ill., assignors to Sunbeam Corporation, Chi-
cago, Ill., a corporation of Illinois

Filed Feb. 13, 1959, Ser. No. 54,600

Term of patent 14 years

(Cl. D54—14)

FIG. 1 is a side perspective view of a portable electric drill unit showing our new design;

FIG. 2 is a side elevational view thereof;

FIG. 3 is a front elevational view thereof;

FIG. 4 is a rear elevational view thereof; and

FIG. 5 is a top plan view thereof.

The essential features of our design reside in those portions shown in full lines.

We claim:

The ornamental design for a portable electric drill unit, substantially as shown and described.
